UNITED STATES PATENT OFFICE.

DORSEY F. ASBURY, OF BROOMES ISLAND, MARYLAND.

GEARING.

Application filed February 27, 1926. Serial No. 91,197.

My invention relates to adjustable means adapted to be arranged between a movable part and an operator therefor whereby movement of a predetermined portion of the operator at a constant rate of speed may be caused to move the movable part at different variable speeds, my invention finding particular utility in connection with the collective operation of the movable parts of a plurality of radio tuning units, which tuning unit parts as a rule require variable movement with respect to one another to cause them to tune simultaneously with different wave lengths.

More particularly my invention consists in the provision of an arrangement in which a part to be moved is equipped with a member having peripheral contact with an operator, and an eccentric for shifting the position of the member with respect to the movable part to vary the distance between the latter and any selected point in the periphery of the member, whereby a predetermined amount of movement of the operator may be caused to impart different amounts of movement to the movable part.

As directed to the operation of the movable parts of radio tuning units, my present invention is designed as an improvement in certain respects over the means disclosed for example in my prior applications 683,756; 690,795 and 80,833 for causing the movable parts of a plurality of tuning units to be moved varying amounts with respect to one another during collective operation of such units, and in other respects is an improvement over the adjustable means for a like purpose disclosed for example in my prior applications 89,441; 89,442 and 89,443, my present arrangement being designed with particular reference to simplicity of construction, cheapness and ease of manufacture and facility of adjustment.

My inventive idea is capable of embodiment in different mechanical structures, certain of which are illustrated in the accompanying drawings, but it is to be understood that the structures shown are merely intended to disclose the essential features and novel characteristics of my invention in certain preferred forms and that its scope is as defined in the appended claims.

In the drawings, wherein like characters of reference denote corresponding parts in the different views:-

Fig. 1 is an elevation showing an adaptation of my invention to each of a plurality of radio tuning units connected together for collective operation;

Fig. 2, a plan view of the structural arrangement shown in Fig. 1;

Fig. 3, an enlarged section on the line 3—3 of Fig. 1;

Fig. 4, a detail perspective of the eccentric element of my invention showing same separated from the movable part upon which it is adapted to be secured;

Fig. 5, a fragmentary elevation showing a slightly modified form of my invention; and

Fig. 6, a section on the line 6—6 of Fig. 5.

In the adaptation of my invention to a radio tuning unit, to a variable plate condenser for example, I mount for rotatable adjustment on the rotor shaft 10 of the condenser an eccentric element 12 and on said eccentric element I mount a gear wheel 14 and an arm 16. Gear wheel 14 is free with respect to eccentric element 12, so as to be rotatable with respect thereto at any time, while any preferred means may be employed, such, for example, as a set screw 18 threaded in arm 16 for contact with eccentric element 12 to secure said arm in any rotatably adjusted position with respect to said eccentric element. Likewise, any preferred means may be employed to secure eccentric element 12 in any desired rotatably adjusted position with respect to shaft 10, a preferred means consisting as shown of a screw 20 threaded in the end of shaft 10, said screw having a tapered head and said shaft being split for a portion of its length whereby tightening of said screw will spread said shaft against said eccentric member.

Arm 16 has rotatably mounted therein a shaft 22 carrying an eccentric 24 which is received in a slot 26 in gear wheel 14, and an operating handle 28 is provided on shaft 22 for rotating same, the result being that if gear wheel 14 is held against movement and handle 28 is rotated to rotate eccentric 24, said eccentric will react from said gear wheel to swing arm 16 and thus rotate shaft 10 due to the fact that said arm is secured to eccentric element 12 and said eccentric element is secured to said shaft. On the other hand, if gear wheel 14 is rotated its rotation will be transmitted through eccentric 24, arm 16 and eccentric 12 to shaft 10.

10, provided, of course, some means is employed to hold eccentric 24 against rotation with respect to arm 16, such means being provided in this instance in the form of a 5 spring washer 30 interposed between handle 28 and arm 16 and engaging these parts with sufficient friction to hold eccentric 24 against rotation when gear wheel 14 is rotated.

10 The hole in gear wheel 14 that receives eccentric 12 preferably is concentric with respect to the periphery of said gear wheel, and the latter preferably is of circular shape although it may be of irregular shape if desired, the essential characteristic of my invention in so far as these features are concerned being that by rotatably adjusting eccentric 12 on shaft 10 any desired point in the periphery of gear wheel 14 may be 15 shifted towards or away from shaft 10 whereby a predetermined amount of movement of an operator engaging the periphery of said gear wheel may be caused to impart different amounts of rotation to shaft 10, it 20 being manifest that if the distance between the operator and shaft 10 is shortened a given amount of movement of the operator will impart a greater amount of rotation to shaft 10 than the same amount of movement 25 of said operator would impart to said shaft if the distance between the shaft and operator were lengthened.

Arm 16 terminates in a pointer 32 adapted for cooperation with graduations 34' provided on some fixed surface such, for instance, as a panel board 34, and for this reason said arm is rotatably adjusted on eccentric 12, so that irrespective of the rotated position of said eccentric with respect to shaft 10, said arm may be rotatably adjusted on said eccentric to bring pointer 32 in alignment with a desired graduation 34'. Otherwise arm 16 might be formed as an integral part of eccentric 12 or be permanently secured thereto.

In Figures 1 and 2 I have shown a plurality of tuning units constructed as described and arranged for collective operation by a common operator in the form of a rack bar 36 engaging the periphery of the gear 14 of each unit, said rack bar being flexible and being supported by yieldably mounted rollers 38 whereby it will remain in driving contact with each gear wheel despite eccentric movements of the same during rotation thereof.

The intermediate gear wheel 14 is shown in Fig. 1 as adjusted by its eccentric 12 to the greatest distance possible between the point 60 on its periphery in contact with rack bar 36 and shaft 10, so that if the rack bar is shifted in either direction the speed of shaft 10 will progressively increase during movement of the rack bar at a constant speed. The left hand gear wheel 14 as viewed in Fig. 1 is

shown on the other hand as being adjusted by its eccentric so that its speed will be increased as rack bar 36 is moved to the left and decreased as said rack bar is moved to the right, while the right hand gear wheel 14 70 as viewed in Fig. 1 is shown adjusted by its eccentric 12, so that its speed will be decreased as rack bar 36 is moved to the left and increased as said rack bar is moved to the right. Thus it is apparent that by properly adjusting eccentrics 12 a given amount of movement of rack bar 36 may be caused to move the movable part of each tuning unit substantially the exact amount required to cause all units to tune simultaneously with any given wave length, despite the fact that more or less movement of one or more of the movable parts with respect to another may be required to accomplish this result. 75 The eccentrics 24 provide vernier means whereby the movable parts of the tuning units may be individually adjusted, since in any plural unit arrangement embodying more than two units the resistance of the movable parts of a plurality of units will always be present to hold rack bar 36 and consequently the gear wheel 14 of the unit to be individually adjusted against movement, so that any given eccentric 24 will react when rotated from its associated gear wheel 14 to rotate its associated shaft 10.

In Figures 5 and 6 of the drawings I have shown an arrangement which is essentially the same as the preferred arrangement illustrated in Figures 1 to 4, but which differs from said preferred arrangement in that instead of arm 16 carrying an eccentric 24 operating in a slot in gear wheel 14, said arm is equipped with a pinion 40 engaging the peripheral teeth of said gear wheel. Otherwise the construction and mode of operation is the same as described in connection with the preferred form of my invention.

I claim:

1. In mechanism of the class described, a 110 rotatable shaft, an eccentric rotatably adjustable on said shaft, a gear wheel rotatably adjustable on said eccentric, and a rack for driving said gear.

2. In mechanism of the class described, a 115 rotatable shaft, an eccentric rotatably adjustable on said shaft, a member carried by said eccentric, and means operable through said member and said eccentric to drive said shaft.

3. In mechanism of the class described, a rotatable shaft, an eccentric rotatably adjustable on said shaft, a disk rotatably adjustable on said eccentric, and a reciprocal operator engaging the periphery of said 125 disk for rotating same.

4. In mechanism of the class described, a rotatable shaft, a disk carried by said shaft, a reciprocal operator engaging the periphery of said disk for rotating same, and ad- 130

justable means whereby any predetermined point in the periphery of said disk may be shifted towards and away from said shaft.

5. In mechanism of the class described, a movable part, a member rotatable to move said movable part, a flexible reciprocal operator coacting with the periphery of said member for rotating same, and means to vary the distance between the axis of rotation and any point in the periphery of said member whereby the coaction of said operator with a predetermined portion of the periphery of said member may be caused to produce different amounts of movement of 15 said movable part.

6. In mechanism of the class described, a movable part, a member rotatable to move said movable part, a reciprocal operator coacting with the periphery of said member for rotating same, means for shifting the axis of rotation of said member with respect to the periphery thereof and yieldable means holding said operator in driving engagement with the periphery of said member.

25 7. In mechanism of the class described, a plurality of movable parts, a member associated with each movable part for moving the same, an operator for moving said members collectively, and eccentric means for 30 adjusting said members whereby a predetermined amount of movement of said operator may be caused to produce varying amounts of movement of said movable parts with respect to one another.

8. In mechanism of the class described, a 35 plurality of movable parts, a member associated with each movable part rotatable to move the same, an operator coacting with the peripheries of a plurality of said members for rotating same, and means for adjusting said members whereby the same coaction of said operator with a predetermined portion of the periphery of each member may be caused to produce varying amounts of movement of said movable parts 45 with respect to one another.

9. In mechanism of the class described, a rotatable shaft, an eccentric on said shaft, a member rotatable on said eccentric, a second member secured against rotation with 50 respect to said shaft and said eccentric, and means connecting said members operable to rotatably adjust them with respect to one another.

10. In mechanism of the class described, a 55 rotatable shaft, an eccentric mounted for rotatable adjustment on said shaft, means to secure said eccentric to said shaft, a member at all times rotatable on said eccentric, a second member mounted for rotatable adjustment on said eccentric, means to secure said second member to said eccentric, and means connecting said members operable to rotatably adjust them with respect to one another. 60 65

In testimony whereof I hereunto affix my signature.

DORSEY F. ASBURY.
